UNITED STATES PATENT OFFICE.

WELCOME P. GAMMONS, JR., AND GEORGE S. BRACHER, OF NEW YORK, N. Y.

HAT-SEWING MACHINE.

SPECIFICATION forming part of Letters Patent No. 650,313, dated May 22, 1900.

Application filed August 4, 1898. Renewed October 28, 1899. Serial No. 735,128. (No model.)

To all whom it may concern:

Be it known that we, WELCOME P. GAMMONS, Jr., and GEORGE S. BRACHER, citizens of the United States, residing at New York, 5 in the county of New York and State of New York, have invented new and useful Improvements in Hat-Sewing Machines, of which the following is a specification.

Our invention relates to sewing-machines 10 for attaching bindings to the curled or rolled brims of hats, and is designed more particularly as an improvement upon the machine disclosed in the Letters Patent granted to us under date of October 12, 1897, No. 591,754.

15 The general object of the present invention is to provide a sewing-machine constructed with a view of expeditiously attaching binding to the brims of those hats which are equipped with wires at the inner sides of 20 their brims for the purpose of increasing the flexibility of the same.

With this end in view the invention will be 25 fully understood from the following description and claims when taken in conjunction with the annexed drawings, in which—

Figure 1 is a perspective view of a sewing-machine embodying our improvements. Fig. 2 is a detail longitudinal section, on an enlarged scale, of the work-supporting arm. Fig. 3 is a horizontal section taken in the plane indicated by the line 3 3 of Fig. 2. Fig. 4 is a detail perspective view of the plate which normally covers the shuttle-race. Fig. 5 is a detail perspective view of the gage. Fig. 6 is a similar view of the cam through the medium of which the gage is adjusted and held 35 in its adjusted position. Fig. 7 is a plan view of a portion of a hat-brim equipped with a wire and having its edge covered by binding, the 40 same being shown simply for the purpose of imparting a clear understanding of the invention which resides in the machine. Figs. 8 and 9 are detail transverse sections taken in the planes indicated by the lines 8 8 and 9 9, 45 respectively, of Fig. 7, and showing the binding in the position it assumes before being turned over upon the brim. Fig. 10 is an inverted plan view of the machine on a reduced scale. Fig. 11 is a detail longitudinal section 50 of the base portion of the machine. Fig. 12 is a transverse section taken in the plane indicated by the line 12 12 of Fig. 10. Fig. 13

is a detail section taken in the plane indicated by line 13 13 of Fig. 2. Fig. 14 is a perspective view of the bobbin removed from the 55 shuttle. Fig. 15 is a perspective view of the shuttle with the bobbin removed. Fig. 16 is a perspective view of the base or washer through the medium of which the shuttle is oscillated. 60

Referring by letter to said drawings, A is the machine-base, and B is an overhanging arm having a head C at its forward end, in which are arranged a needle-bar D, a presser-bar E, having a foot *a* at its lower end, and a 65 feed-bar F. The needle-bar, presser-bar, and feed-bar are similar to those embodied in sewing-machines at present in use, and the needle-bar and feed-bar are operated by a driving-shaft G through the medium of mechanism contained in the head C, the needle-bar D being reciprocated vertically and the feed-bar F moved up and down and forward and backward to feed the materials forward. The mechanism through the medium of which the 70 bars D and F are actuated is of the ordinary construction, and it is therefore not deemed necessary to illustrate the same. 75

H is a work-supporting arm which extends 80 forwardly from the base A. It has the rear portion of its under side concave, as indicated by I, to accommodate the crown of a stiff hat to which the binding is being attached, and is made straight, flat, and comparatively thin at its forward end, which rests beneath the 85 needle, feed, and presser bars for a purpose presently pointed out. It also has the corners of its upper side rounded or beveled at its forward end, as indicated by *b*, so that no sharp angles which would tend to injure a 90 hat-brim are presented to the brim as it is fed beneath the needle. The work-supporting arm is further provided with a shuttle-race J. In this race is arranged a shuttle washer or base B', which is provided on its depending 95 stem *b'* with a pinion *c*, intermeshed with the T-rack *d* of a lever C', whereby when the lever is rocked the base or washer will be oscillated. The washer is provided with the usual flange *g* and a spring-pressed lug *g'* 100 thereon, arranged to rest within a marginal recess *h* of the shuttle or shuttle proper D' and transmit oscillatory motion to the same. The shuttle D' has a thread hook or looper *i*

and a spring-strip tension device j for the thread and is further provided with a pocket k for the reception of the bobbin D^2 . The bottom l of this pocket has apertures m , and 5 from its center rises an integral post E' . This post E' is tubular and is split at four (more or less) points, whereby it is rendered resilient and is adapted when the bobbin is placed upon it to exert a constant pressure against 10 said bobbin, and thereby impose uniform tension on the thread irrespective of the quantity of thread upon said bobbin, which is a highly-important advantage, since it obviates the liability of breakage and at the same time 15 renders the stitches even. The said split post E' serves to securely hold the bobbin against casual upward movement in the shuttle and yet does not interfere with the ready removal of the bobbin when desired, such removal being effected by passing a suitable instrument through one of the apertures m of the shuttle and pressing the bobbin upwardly until it can be grasped by the fingers of the operator.

20 The mechanism intermediate of the drive-shaft G and the shuttle-base B' forms an important part of our invention. Such mechanism comprises the lever C' , which is fulcrumed at a^2 , an upright lever C^2 , which is fulcrumed to rock in a transverse plane and is 25 pivotally connected at its lower end to the rear end of the lever C' , and a cam C^3 , which is fixed on the drive-shaft G by a set-screw or other suitable means and is arranged in 30 a fork C^4 at the upper end of the lever C^2 . In addition to affording a very easy and smooth motion in operation the said mechanism, intermediate of the drive-shaft and shuttle is advantageous, because it permits 35 of the forward portion of the lever C' being curved in conformity to the concavity I of the work-supporting arm and arranged between the side flanges of said arm, so as not to offer 40 an obstruction to the crown of a hat placed in the concavity of the arm.

45 L is a plate which rests on the upper flat side of the forward straight portion of the arm H and normally covers the shuttle-race J . This plate L has a slot c' extending in the 50 direction of its width and receiving a threaded post d' on the arm H , and it is designed to be adjustably fixed in its position over the shuttle-race by a binding-nut e , mounted on said post d' . It is further provided, as best shown 55 in Figs. 2 and 4, with a hollow interiorly-threaded post f and a stud-stop g' , and has a recess f' in its forward end, as best shown in Fig. 4, for a purpose presently described.

60 M is a gage against which the edge of the hat-brim is pressed by the operator, as presently described. This gage has a lip h' at its forward end, forming an abutment for the hat-brim, and is provided with a longitudinal slot i' , which receives the post f of covering 65 plate L ; and a notch j' in its rear end receiving the stud-stop g' of said plate L . Said gage is also provided with a lug k' , the same being

disposed in a radial slot l' of a cam N , which is loosely mounted on the post f of plate L and is provided with a finger-piece or handle m' , whereby it may be readily turned. The cam is secured on the post f of the plate L by a screw n , and a spring p is interposed between the head of said screw and the top of the cam and serves to press the cam against 70 the gage, and thereby assists in holding the gage against casual movement when a hat-brim is pressed against the same. The notch j' in gage M and the stud-stop g' of plate L serve in conjunction to hold the gage against 75 lateral movement, while the post f of the plate and the slot i' of the gage serve to limit the endwise movement of the gage, for a purpose presently pointed out.

80 P is a needle-plate which is secured to the end of the work-supporting arm by screws or other suitable means. This plate, in addition to the usual needle-opening r , is provided with a recess or groove s , which is formed in its upper side at its inner edge and 85 is disposed in rear of the needle-opening with respect to the direction in which the materials are fed, as best shown in Fig. 2. Said recess s is designed, in conjunction with the recess f' of the plate L , to form a groove or channel 90 L' for the reception of the hat-brim, as will be hereinafter fully pointed out. The needle-plate P is provided in advance of the needle-opening, with respect to the direction of movement of the materials, with a recess u . (See Fig. 1.) Above the horizontal or bottom wall of the said recess u is disposed the binding-guide Q , which has a depending tail-piece interposed and secured between the needle-plate and the end of the work-supporting arm. 95

100 Referring to Figs. 7, 8, and 9, R is the brim of a stiff hat, and S is a wire with which the brim is provided in order to increase the flexibility of the same. At the front and rear of the brim the wire rests closely adjacent to the edge of the same, as shown in Fig. 8, while at the sides of said brim the wire rests in the rolls or curls at a considerable distance from the edge, as shown in Fig. 9. This 105 renders it necessary to arrange the stitches which connect the binding to the brim between the wire and the crown of the hat, at the front and rear of the brim and between the wire and the edges of the brim, at the 110 sides of said brim. The manner in which this 115 is done will be clearly understood from the following:

120 In the practical operation of the machine the gage M is set back as far as possible from the forward end of the work-supporting arm and the binding is placed in the guide Q , so that its upper portion overlaps the forward end of the work-supporting arm, as shown by dotted lines in Fig. 1. The rear end of the 125 brim of the hat is then placed upon the end of the arm over the binding and its edge is pressed hard against the gage M by the operator when the machine is started and the 130

stitching of the binding is commenced at the point marked 1 (see Fig. 7) and continued until the point marked 2 is reached, with the result that the stitches will be between the wire S and the crown of the hat, as plainly shown in Fig. 7. When the point marked 2 is reached, the machine is stopped and the gage is moved as far as possible forwardly through the medium of the cam N, after which the machine is started and the stitching continued to the point marked 3, when the machine is again stopped. These latter stitches, by reason of the edge of the brim having been moved forward by the gage, will lie between the wire and the edge of the brim and quite close to said edge. At the point 3 the gage is moved back as far as possible or to its initial position and the machine is started and the stitching continued to the point marked 4, the stitches thus formed lying between the wire S and the crown of the hat. When the point 4 is reached, the machine is again stopped and the gage is thrown forwardly as far as possible, after which the machine is started and the stitching continued to the point marked 5, the stitches lying between the wire and the edge of the brim. At the point 5 the machine is again stopped and the gage moved back as far as possible, after which the stitching is resumed until the point 1—*i. e.*, the point of commencement—is reached, these latter stitches lying between the wire and the crown of the hat. While the stitching of the binding to the back end portion of the brim is going on the hat rests or is held with the crown depending; but as the stitching progresses toward and along the side of the brim the hat must be gradually turned until the crown rests in a horizontal or approximately horizontal position with the inside of the hat toward the operator and the crown in the concavity of arm H, and as the stitching further progresses the hat must be turned so that when it reaches the end of the brim opposite to the point of commencement it will rest in the first-mentioned position—*viz.*, with its crown depending. From this point the operation is repeated to the point of commencement. After the piece of binding has been attached along one edge and throughout its length to the inner side of the brim it is then turned over the brim. When thus turned over the brim, the binding will cover and hide the wire at the opposite ends of the brim. During the stitching of the binding from the point 2 to the point 3 and from the point 4 to the point 5 the edge of the brim will be seated in the groove or channel L', formed by the recess f' of plate L and the recess s of the needle-plate, which will hold it against being forced out of its proper position by the strokes of the needle.

By reason of the construction of the gage and the cam for operating the same the changes in the position of the hat-brim with respect to the path of the needle at the points

2, 3, 4, and 5 may be quickly and easily and accurately effected without calculation on the part of the operator, which is an important advantage.

We have entered into a detailed description of the construction and relative arrangement of the parts of our improvements in order to impart a full, clear, and exact understanding of the same. We do not desire, however, to be understood as confining ourselves to such specific construction and arrangement of parts, as such changes or modifications may be made in practice as fairly fall within the scope of our invention. We also desire it to be understood that while the machine is designed more particularly for attaching binding to the brims of those hats which are equipped with wires at the inner sides of their brims it may be used to advantage in attaching binding to the brims of hats which are not provided with wires.

Having thus described our invention, what we claim is—

1. A hat - sewing machine comprising a work-support having a flat portion at its forward end and a concavity at its under side in rear of said flat portion and also having a needle-opening in its flat portion, an open groove or channel arranged in the line of feed and in rear of the needle-opening and adapted to receive the edge of a hat-brim, and a binding-guide arranged in the line of feed and in advance of the needle-opening with respect to the direction in which the materials to be sewed are fed, substantially as specified.

2. A hat - sewing machine comprising a work-supporting arm having a flat portion at its forward end and a concavity in its under side in rear of said flat portion and also having a needle-opening in its flat portion and a hat-guide and a binding-guide arranged the latter in advance and the other in the rear of the needle-opening, a hat-gage arranged on the flat portion of the arm, means for moving said gage forwardly and backwardly, a stop for limiting the forward and backward movements of the gage, and a suitable organized stitch-forming mechanism, substantially as specified.

3. A hat - sewing machine comprising a work-supporting arm having a flat portion at its forward end and a concavity in its under side in rear of said flat portion, a needle-plate connected to the end of the arm and having a needle-opening and a recess in rear of said opening, a horizontal plate arranged on the arm and having a recess serving in conjunction with the recess of the needle-plate to form a hat-guide in rear of the needle-opening, an adjustable hat-gage arranged on said plate, a binding-guide arranged in advance of the opening of the needle-plate and having a tailpiece interposed between the needle-plate and the end of the arm, and a suitable organized stitch - forming mechanism, substantially as specified.

4. A hat-sewing machine comprising a work-support having a flat portion at its forward end and a concavity at its under side in rear of said flat portion and also having a needle-opening and a hat-guide and a binding-guide arranged the latter in advance and the other in the rear of the needle-opening, a hat-gage arranged upon the flat portion of the work-support, and a suitable organized stitch-forming mechanism, substantially as specified.

5. A hat-sewing machine comprising a work-supporting arm having a flat portion at its forward end and a race in said flat portion 15 designed to receive a loop-taker forming part of an organized stitch-forming mechanism, a needle-plate connected to the end of the arm and having a needle-opening and also having a recess *s* in rear of said opening, a binding-20 guide arranged in advance of the opening, a cover-plate arranged on the arm over the race therein and having a post with a threaded socket in its upper end and also having a recess *f'* serving in conjunction with the recess 25 *s* of the needle-plate to form a guideway for a hat-brim, a hat-gage having a slot receiving the post of the cover-plate and also having a lug, an oscillatory cam arranged on the post and having a slot receiving the lug of the 30 gage, a screw taking into the socket of the post, and a spring interposed between the head of the screw and the cam, substantially as specified.

6. In a hat-sewing machine, the combination 35 of a work-supporting arm, a post rising therefrom and having a threaded socket in its upper end, a hat-gage having a slot receiving the post and also having a lug, an oscillating

tory cam mounted on the post and having a radial slot receiving the lug of the gage, a 40 screw taking into the socket of the post, and a spring interposed between the head of said screw and the cam, substantially as specified.

7. In a sewing-machine, the combination of a work-supporting arm, a needle-plate connected to the end of said arm and having a needle-opening and a recess *s* in rear of said needle-opening and a shoulder *u* in advance of the same, a binding-guide arranged in advance of the shoulder and having a tailpiece 50 interposed and secured between the needle-plate and the arm, a horizontal plate arranged on the arm and having a recess *f'* serving in conjunction with the recess *s* of the needle-plate to form a guideway for a hat-brim, an 55 adjustable hat-gage arranged on the horizontal plate, and a suitable organized stitch-forming mechanism, substantially as specified.

8. A hat-sewing machine comprising a 60 work-support having a needle-opening, and a hat-guide and a binding-guide arranged the latter in advance and the other in the rear of the needle-opening, a hat-gage arranged on the work-support and adjustable toward and 65 from the needle-opening, and a suitable organized stitch-forming mechanism, substantially as specified.

In testimony whereof we have hereunto set our hands in presence of two subscribing witnesses.
